Primary Examiner — Doris Clark(74) *Attorney, Agent, or Firm* — David A. Burge(57) **CLAIM**

I claim the ornamental design for a pipe trench side panel, as shown and described.

DESCRIPTION

FIG. 1 is a front perspective view showing my new design, with portions of a central region of the panel that form no part of the claimed design shown by broken lines indicating that the panel has an indefinite length;

FIG. 2 is a rear perspective view thereof;

FIG. 3 is a front elevational view thereof;

FIG. 4 is a top view thereof;

FIG. 5 is a bottom view thereof;

FIG. 6 is a right end view thereof, it being understood that a left end view would be a mirror image of the right end view; and,

FIG. 7 is a sectional view, on an enlarged scale, as seen from a plane indicated by a line 7-7 in FIG. 3, showing a bracket shaped like the numeral “7.”

The design relates to short opposite end regions and to a short central region of a side panel that is used in forming a pipe trench. The three short regions of the claimed design are connected by intervening structure that forms no part of the claimed design.

All subject matter depicted by broken lines is environmental, is provided for merely for illustrative purposes, and forms no part of the claimed design.
